UNITED STATES PATENT OFFICE

EARL W. LITTLE, OF INDIANAPOLIS, INDIANA

DESIGN FOR A BIRD CAGE

Application filed November 8, 1929. Serial No. 33,379. Term of patent 14 years.

To all whom it may concern:

Be it known that I, EARL W. LITTLE, a citizen of the United States, residing at Indianapolis, in the county of Marion and State of Indiana, have invented a new, original, and ornamental Design for Bird Cages, of which the following is a specification, reference being had to the accompanying drawing, forming part thereof.

The figure is an elevational view of a bird cage, showing my new design.

I claim:

The ornamental design for a bird cage, as shown.

EARL W. LITTLE.
